CONTAINER

James D. Gerahy, New York, N. Y.

Application March 13, 1943, Serial No. 479,007

8 Claims. (Cl. 229—5.5)

The present invention has for its object the production of a container of simplicity of construction and of few parts which shall be adapted to receive any one of a plurality of commodities of varying physical and chemical characteristics for purposes of storage and/or shipment and which may be manufactured with facility and expedition at relatively small expense.

A further object of the invention is the production of a container of the above character the component parts or elements of which shall be of a non-metallic nature thereby effecting a material saving in metal which now constitutes a vital and important necessity for war purposes.

Still a further object of the invention is the production of a container having the above characteristics which shall be hermetically sealed to provide an air-tight and leak-proof package not only enabling it to be employed for the storing and/or shipping of liquids but also preventing deterioration of its contents irrespective of the physical and chemical characteristics thereof.

Another object of the invention is the production of a container of the character referred to above which shall be provided with a double-flanged or double-walled closure providing a groove for snugly receiving and supporting both sides of an end of the body of the container, both flanges or walls being of substantially equal strength enabling the closure to act as an effective seal for the container resistant to forces or pressure applied thereagainst or to the body of the container.

Other and further objects and advantages of the invention will become apparent from the following description, the invention consisting in the novel container and combinations of parts thereof and in the method of applying the closure to the body thereof hereinafter more particularly described and then specified in the claims.

In the accompanying drawing showing a practical embodiment of the invention:

Fig. 1 is a top plan view (partly broken away) of the container of the invention.

Fig. 2 is a horizontal section on the line 2—2 of Fig. 1.

Fig. 3 is a vertical section on the line 3—3 of Fig. 1.

Fig. 4 is a fragmentary section of a portion of the body and closure.

Fig. 5 is a top plan view of a modification.

Fig. 6 is a horizontal section on the line 6—6 of Fig. 5.

Fig. 7 is a top plan view (partly broken away) of a further modification, and

Fig. 8 is a section on the line 8—8 of Fig. 7.

Referring in detail to the several figures of the drawing:

The body of the container is preferably cylindrically shaped to form an open drum or cylinder

and is indicated at 10. It is rigid in character and preferably is constructed of paper, fiber or any other analogous nonmetallic material. For convenience said body 10 is provided in the preferred form of the invention with a base and cover constituting closures which may be identical in construction. Each of said closures is constructed of a non-metallic plastic material having strength, rigidity and lightness in weight 10 and which is resistant to fracture or cracking. The body may be molded from a suitable resin which is hardened in any desirable manner after it has been fashioned or molded to its proper configuration. For the purposes of the invention 15 acetate resins and phenolic resins will be found to be peculiarly desirable, the use of an acetate resin being preferred because of the lightness in weight of the finished product and because it is substantially colorless and transparent.

20 The closure just referred to comprises a circumferential rim 11 for the body provided with a downwardly depending annular flange 12 and a horizontally disposed disc-like imperforate plate 13 both integral with said rim. Said plate 13 is 25 provided with a downwardly depending annular flange 14 integral therewith forming a groove 15 of material depth with the flange 12 for snugly and frictionally receiving the upper end, or lower end as the case may be, of the body 10. 30 The plate-like disc 13 is provided with diametrically opposed cup-shaped adhesive-receiving and adhesive-applying open wells 16 or analogous elements the walls of which are integral with the plate 13 and flange 14 and are 35 formed with the closure during the molding operation thereof. These wells are open at their outer sides so as to communicate freely with the groove 15 and the base of each well lies adjacent the free edge of the flange 14. When the closure 40 is received by an end of the body 10 which enters and snugly interfits with the groove 15, as has been explained, the base of each well 16 will lie in substantial alignment with one of a pair of diametrically opposed locking slots 17 cut, or 45 otherwise formed, in the body 10 adjacent either free end thereof.

When the closure is placed on an end of the body in close and firm engagement therewith in the manner explained, the wells 16 are filled with 50 liquid adhesive which may be the liquid resin itself from which the closure is constructed. The closure is then rotated through an arc of 180° or more so that the adhesive in the wells will be applied to the inner surface of the end of the body adjacent the flange 14 and will be spread as a thin film on the inner surface of the body 10 and outer surface of the flange 14 over a continuous circumferential area having a depth substantially equal to the depth of the slot 17 in 55 the body. Rotation is discontinued when the 60 body.

wells have been brought into alignment with the slots 17 to permit the liquid adhesive to flow from the wells into and fill said slots 17 which, of course, are closed by the flange 12. The adhesive is then allowed to harden and thereby lock the closure to the body by a circumferential adhesive seal and by the additional hardened adhesive which enters the slot 17 and adheres to the flange 12 and which act as bolts 17² interfitting with said slots, said bolts having strengthening heads 17³ formed by the hardened adhesive remaining in the wells 16 (see Fig. 2). The sealed connection between the parts is thus materially strengthened and any disconnection therebetween as well as relative rotation of one part with respect to the other is effectively resisted. In addition, this manner of sealing is particularly desirable in that the sealing adhesive does not enter the container so that any possible contamination of the contents thereof is obviated.

The container just described is more particularly adapted for holding liquids and as the closures therefor are not removable for practical purposes without breakage or considerable mutilation thereof, access to the contents of the container may be had by boring or otherwise forming a bung-hole (not shown) at any convenient portion of the body 10 which, if so desired, may be interfitted with a spigot or other suitable dispensing device.

The container of the modification of Figs. 5 and 6 is also more especially adapted for shipping and storing liquids and access may be conveniently had thereto without mutilation or disfigurement of the body 10 or of the closure per se. In this case the rim is provided with inwardly directed locking ears or similar elements 18 integral therewith and the plate 13 of the closure is provided with diametrically opposed openings 19 extending therethrough and communicating with the interior of the container. The closure is provided with cup-shaped adhesive-receiving wells or elements 16 and the body 10 with slots 17 (not shown) as in the preferred form of the invention so that the closure may be adhesively connected and sealed to the body as in said preferred form.

A closure disc 20 engages and seats on said plate 13 to normally close the openings 19 and it interfits with the inner peripheral surface of the rim 11. For convenience of placement, it may be provided with oppositely disposed cut-out portions of a size and configuration to receive the locking ears 18. To lock the closure disc in seated position in engagement with the plate 13 a locking plate 21 has been provided. This locking plate is so constructed as to form diametrically and oppositely disposed tabs 22 having arcuate ends conforming in configuration with that of the inner circumferential surface of the rim 11 with which they slidably interfit. When the locking plate 21 is in locked position it compresses against the closure disc 20 with two of said tabs 22 covering and closing the adhesive-receiving wells 16 and the other two tabs thereof engaging beneath the ears 18 in locking position.

As is manifest, those portions of the locking plate 21 intermediate its tabs 22 are cut away or so formed as to provide convenient finger grips to permit rotation and removal of the plate 21 when so desired by disengagement of the tabs with and from beneath the ears 18. When the locking plate 21 and closure disc 20 are removed the liquid contents of the container may be withdrawn by tilting the container whereby the con-

tents will flow from one of the openings 19, the other of said openings being provided for the admission of air as customarily.

The modification of the container illustrated in Figs. 7 and 8 is adapted to hold solids or semi-solids and the closure is applied and hermetically sealed to the body in the same manner as shown and described with respect to the preceding forms of the invention, it being provided with the adhesive-receiving wells or cups 16 while the body is provided with the slots 17 (not shown). In this case the disc-like plate 13 is provided with an enlarged circular opening 23 and is shouldered as at 24 for receiving a removable closure disc 25 which seats on and interfits with said shoulder. An annular rotatable locking plate is indicated at 26 and is adapted to interfit within the rim 11 and to lock beneath the locking ears 18 on the rim 11 as in the case of the device of Figs. 5 and 6.

Said locking plate 26 is also provided with two or more cut-away portions 27 for reception of the locking ears 18 to permit placement of the plate within the rim 11 prior to its being rotated into locked position. These cut-away portions may also serve as finger grips for rotating the plate in some cases. The underside of the locking plate 26 is provided with an annular gasket or washer 28 adapted to engage and be compressed against the closure disc 25 to prevent unseating thereof from the shoulder 24 and to seal and close the opening 23 when the parts are in closed and locked position. Said gasket 28 may comprise any suitable compressible material.

It will be further understood that the closure discs and locking plates or elements of Figs. 5 to 8 inclusive may be composed of any suitable strong material but it is preferred that the material shall be non-metallic in character and in keeping with one of the general objects of the invention of producing a container of strength which shall be devoid of metal or metal parts.

Obviously, in the case of the modifications of Figs. 5 to 8 inclusive, the base of the container may be constructed in accordance with the closure described and shown with respect to Figs. 1 to 4 inclusive or any other base may be employed. In addition, the closure of Figs. 5 and 6 may be used for one end of the body and the closure of Figs. 7 and 8 for the other end thereof so that the contents of the container may be dispensed in small amounts or in large volume to suit one's convenience. Manifestly, also, the body 10 and the closures or parts thereof may be chemically or otherwise treated to enhance their strength or to insure preservation of the contents of the container in the proper and desired condition.

In the case of the modification of Figs. 5 and 6, it is obvious that the closure disc 20 may be dispensed with in which case the locking plate 21 will act not only as the locking element per se, but as the closure element as well. In this case the tabs 22 might carry any suitable form of gaskets or washers (not shown) adapted to close the openings 19 and the adhesive-receiving wells 16.

The invention claimed is:

1. In a container, a non-metallic cylindrical body provided with a base secured thereto and a closure constructed of hardened liquid resin and consisting of a horizontally disposed plate and substantially parallel inner and outer flanges integral with the plate and forming a concealed groove receiving an end of said body, a cup-shaped adhesive-receiving well integral with said

closure and communicating with said groove, said body and one of said flanges being secured together by a circumferential layer of adhesive intermediate the ends of the flange and body and by adhesive connecting said well and body.

2. In a container, a non-metallic cylindrical body provided with a base secured thereto and a closure constructed of hardened liquid resin and consisting of a horizontally disposed plate and inner and outer spaced flanges integral therewith extending transversely of said plate and forming a groove snugly receiving an end of said body and an adhesive-holding element integral with said inner flange and communicating with said groove, said body and one of said flanges being connected together by adhesive extending thereto from said element.

3. In a container, a non-metallic cylindrical body provided with a base secured thereto and a closure constructed of hardened liquid resin and consisting of a horizontally disposed plate and inner and outer spaced flanges integral therewith extending transversely of said plate and forming a groove snugly receiving an end of said body and diametrically disposed cup-shaped adhesive-holding wells integral with said inner flange and communicating with said groove, said body and closure being connected together by adhesive extending from said well to said body.

4. In a container, a non-metallic cylindrical body having a slot therein provided with a base secured thereto and a closure constructed of hardened liquid resin and consisting of a horizontally disposed plate having inner and outer spaced flanges integral therewith and extending outwardly from said plate and forming a groove of substantial depth snugly receiving an end of said body, a cup-shaped adhesive-holding well integral with said inner flange and a headed bolt comprising hardened adhesive extending from said well and into the slot in said body.

5. In a container, a non-metallic cylindrical body provided with a base secured thereto and a non-metallic closure consisting of a horizontally disposed plate having openings therein, spaced flanges integral with the closure forming a groove snugly receiving an end of said body, an adhesive-receiving element integral with said closure and communicating with said groove, a

locking element and a rotatable member adapted to close the openings in said plate and said adhesive-receiving element and to interlock with said locking element.

5 6. In a container, a non-metallic cylindrical body provided with a base secured thereto and a closure constructed of hardened liquid resin and consisting of a horizontally disposed plate having spaced openings therein, said closure also being provided with inner and outer spaced flanges integral therewith forming a groove snugly receiving an end of said body, diametrically opposed cup-shaped adhesive-receiving elements integral with said inner flange and communicating with said groove, locking elements on said closure spaced from said plate and a detachable rotatable disc provided with tab members adapted to lockingly engage said locking elements and to cover the aforesaid openings and said adhesive-receiving elements.

7. In a container, a non-metallic cylindrical body provided with a base secured thereto and a closure constructed of hardened liquid resin and consisting of a plate having an enlarged opening therein and said closure being also provided with inner and outer spaced flanges integral therewith forming a groove receiving said body, an adhesive-receiving element integral with one of said flanges and communicating with said groove, 25 a locking element on said closure, a seat adjacent said enlarged opening, a removable closure disc engaging said seat and a detachable locking plate interlocked with said locking element and normally covering said adhesive-receiving element and holding said closure disc in closed position on its seat.

8. In a container, a body having a slot extending transversely therethrough and provided with a base secured to said body and a closure interfitting with said body and consisting of a plate and inner and outer spaced flanges connected thereto and forming a groove snugly receiving the end of said body remote from said base and an adhesive-holding well carried by one of said flanges and communicating with said groove, said body, well and said one of said flanges being held together by suitable adhesive extending from said well and into said slot.
